UNITED STATES PATENT OFFICE.

ALFRED LEANDER RIGGS, OF PITTSBURGH, PENNSYLVANIA.

SPARK-PLUG.

1,355,427.

Specification of Letters Patent. Patented Oct. 12, 1920.

Application filed June 27, 1919. Serial No. 307,240.

To all whom it may concern:

Be it known that I, ALFRED LEANDER RIGGS, a resident of Pittsburgh, in the county of Allegheny and State of Pennsylvania, have invented a new and useful Improvement in Spark-Plugs, of which the following is a specification.

This invention relates to spark plugs of the type in which an auxiliary spark gap is provided at the upper end of the plug and which is visible so that it can be seen whether current is being supplied to the electrodes or is being short circuited for any reason. The present invention is an improvement of my Patent No. 1,265,518, granted May 7, 1918, and reissued October 15, 1918, No. 14,538.

The primary object of the present invention is to provide a spark plug of the above named type in which the auxiliary spark attachment is simpler and cheaper to manufacture and to apply to the insulating core than in such plugs as heretofore constructed.

25 In the accompanying drawings Figure 1 is a side elevation of the upper portion of a plug showing the improvement applied thereto; Fig. 2 is a central vertical section therethrough; Fig. 3 is a vertical sectional view taken on the line 3—3, Fig. 1; Fig. 4 is a horizontal section taken on the line 4—4, Fig. 1; and Fig. 5 is a similar view showing a modification.

In the drawings 10 represents the upper portion of the porcelain or other insulating core of the plug. This is provided with a flat top end face and with a central axial bore and near the upper end with an external annular groove 11.

40 Mounted upon the core is a cap or sleeve 12, the lower end of which is crimped or flanged inwardly, as at 13, to engage in the groove 11 of the core. The upper end of this cap or sleeve is likewise crimped or flanged inwardly, as at 14, and slightly below its upper end said cap or sleeve is contracted, forming an internal shoulder 15. A disk of glass or other transparent material 16 has its edge set in the groove formed 45 by the inturned flange 14 and internal shoulder 15. In order that said glass may be tightly wedged in said groove and prevented from rattling, its edge is preferably beveled on both sides, as shown at 17, in 50 order that it may wedge into the groove. To facilitate formation of the bottom flange

13 and top flange 14 the metal of the edges of the sleeve is preferably provided with a series of V-shaped slits or notches extending into the material only a short distance and which permit the portions of the edges of the metal between said slits or notches to be readily flanged or bent inwardly.

Within the sleeve 12 in firm electrical contact therewith and resting upon the top surface of the core is a terminal ring 18, provided with an inwardly projected sparking point 19, which co-operates with the upper end of metal rod 20 extending down through the axial bore in the core and which rod 70 forms one terminal of the main spark gap. The space between the upper end of this rod and the projection 19 of the ring 18 forms the auxiliary spark gap which is visible through the glass 16 in order that the character of the spark can be observed. This ring 18 may be either a solid ring, as shown in Fig. 4 or may be a wire bent to ring form as shown at 18^a, Fig. 5, having one end turned inwardly to form the spark 80 terminal 19^a.

The sleeve or cap 12 is split along one side, shown at 21, and is clamped to the core, and at the same time clamps the glass 16 and ring 18, by means of a pair of radially extending ears 22 and 23, one formed on each edge of said sleeve, by bending a tongue of the metal radially. These ears are perforated to receive a clamping bolt or screw 24 which enters a threaded hole in a block 25 from which projects the binding-post 26 to which the ignition wire is secured. The block 25 serves as a nut. This block is made square or of other polygonal form and to keep it from turning when tightening 90 the clamp screw 24 the lower edge of the ear 23 is bent outwardly, as at 27, and bears against the lower face of said nut. Preferably the cap or sleeve is provided with a series of ventilating openings 28.

100 The cap or sleeve 12 can be very cheaply manufactured by blanking it out from sheet metal having projecting ears 22 and 23 at opposite sides thereof, and then bending said blank to tubular form and crimping inwardly the portions 13, 14 and 15. Said cap or sleeve is secured to the core by means of the screw 24 and nut 25, and this act also serves to clamp tightly in position the glass 16 and terminal ring 18. 110 This construction required a minimum number of parts thus decreasing material and

labor, resulting in a low cost of production. At the same time it can be securely attached to the core and also securely holds the glass and terminal ring.

5 I claim:

1. In a spark plug, a sleeve for mounting upon an insulating core, said sleeve being slit longitudinally and provided on each edge at the slit with a perforated radial ear, a binding-post provided with a threaded opening, and a clamping screw extending through the perforated ears and engaging the threaded opening of the binding-post and securely clamping said cap to the core and securing said binding post to said sleeve.

2. In a spark-plug, a sleeve arranged to be mounted upon an insulating core, said sleeve being slit vertically and provided at each edge at said slit with a radial perforated ear, one of said ears having its lower edge turned horizontally, a binding-post having a non-circular portion engaging the out-turned portion of said ear and provided with a threaded opening, and a clamping screw passing through the perforated ears and engaging the threaded opening of the binding-post.

3. In a spark plug, the combination with an insulating core provided with an axial bore and with an external annular groove near its upper end, a rod extending through said axial bore, a sleeve having an in-turned lower edge engaging with the annular groove in the core, an inturned upper edge, an inwardly projecting shoulder slightly below its upper edge and being split vertically and provided on each edge with a perforated radial ear, a terminal ring in said sleeve and coöperating with the upper end of said rod, a transparent pane having its periphery held between the in-turned upper edge of the sleeve and the internal

shoulder adjacent thereto, and a clamping screw and nut coöperating with the perforated ears for clamping said sleeve to the core and clamping the terminal ring and transparent pane in said sleeve.

4. In a spark plug, in combination, an insulating core provided with an external annular groove near its upper end, a metal rod extending through said core and projecting above its upper end, a sleeve having an in-turned lower end engaging in the annular groove in the core, said sleeve being split vertically and provided at each edge at said slit with a radial perforated ear, a terminal ring in said sleeve in contact therewith and coöperating with the upper end of said rod, a transparent pane in the upper end of said sleeve, a binding-post provided with a threaded opening, and a clamping screw extending through the perforated ears and engaging the threaded opening of the binding-post and serving to clamp the sleeve on the core and clamp the terminal ring and transparent pane in said sleeve.

5. In a spark plug, in combination, an insulating core provided with an external annular groove near its upper end, a sleeve having an in-turned lower end engaging in said groove, said sleeve being split vertically and provided at each edge at said slit with a radial perforated ear, a binding post provided with a threaded opening, and a clamping screw extending through the perforated ears of the sleeve and engaging the threaded opening of the binding post and serving to clamp the sleeve on the core and secure the binding post thereto.

In testimony whereof I have hereunto set my hand.

ALFRED LEANDER RIGGS.
